UNITED STATES PATENT OFFICE.

THOMAS D. PILCHER, OF WASHINGTON, DISTRICT OF COLUMBIA.

WATER HEATER.

Application filed July 5, 1921, Serial No. 482,505. Renewed October 10, 1922. Serial No. 593,658.

To all whom it may concern:

Be it known that I, THOMAS D. PILCHER, a citizen of the United States, residing at Washington, in the District of Columbia, 5 have invented certain new and useful Improvements in Water Heaters; and I do hereby declare the following to be a full, clear, and exact description of the invention, such as will enable others skilled in the art 10 to which it appertains to make and use the same.

The object of the invention generally is the provision of a heater wherein more of the generated heat energy than usual shall 15 be transmitted to the medium to be heated and not be discharged to the atmosphere and wasted.

Specifically the object is the provision of an apparatus for heating water or other 20 fluid wherein the current of the heat bearing medium employed, such as air and gases mingled with the products of combustion and raised to a high temperature, shall be retarded and caused to engage a relatively 25 large area of heat receiving surface, but such retardation not be sufficient to injuriously impair the draft and cause the discharge of heated gases and smoke at the entrance end for such heat bearing medium.

30 In carrying out the invention use is made of the principle that fluids in motion, such as air and the like, tenaciously cling to the surfaces over which they move in frictional contact, following the irregularities and changes 35 of direction of such surfaces, rather than at once passing to the open space or spaces adjacent such surfaces.

The invention consists in certain novelties of construction and in the combination of 40 parts herein set forth and claimed.

The accompanying drawing illustrates an example of the embodiment of the invention, the parts being constructed and relatively combined according to the best of the several 45 modes of procedure I have so far devised for the purpose.

Figure 1 is a vertical section in elevation of a hollow cylindrical tank for water and a 50 hollow heating flue located concentrically or axially therein, parts at the top and bottom of said flue being broken away to show the interior.

Figure 2 is a view of the tank shown by Figure 1 and a slightly modified form or 55 construction of the flue shown by Figure 1, the view being substantially the same except

that the top part of the flue wall only is shown in section.

Referring to both figures, the parts common to both are designated by the same characters. A is a hollow cylindrical metallic tank either of wrought or cast metal having a top perforated outwardly projecting circular flange B and a similar bottom perforated flange C to receive rivets. The interior of the tank is to contain water or other fluid to be heated, and to provide for the circulation of the fluid through a coil or closed pipe one end of said pipe D is secured in the wall of the tank near the bottom thereof and 60 the opposite end E is secured in the wall near the top end, the heated water passing out of the top of the tank at the end E and returning to the interior thereof through the end D, as is well known.

Axially located relative to and within the tank is a hollow heating flue F of cast or wrought metal. Said flue at its ends may be exteriorly threaded at G G to receive threaded flanges H H of top and bottom heads I 70 and J, said heads being circular in outline and perforated as shown. Rivets R passed through the perforations in the heads and the perforations in the flanges B and C of the tank close the ends of the tank and the 75 heads hold the flue F in position.

Each of the flues has one or more hollow enlargements S intermediate its ends, two such enlargements being shown in each figure. In Figure 1 the lower, top, and intermediate parts of the flue, designated by T, U and V, are of the same diameter and the cross sectional areas the same. In Figure 2 the lower part W and the intermediate part X of the flue are of the shapes shown and 90 each gradually increases in diameter upwardly so that the cross sectional areas of said parts at Y Y where they join the enlargements S, S are of greater cross sectional area than at any section below.

It will be noted that each of the enlargements S gradually increases in diameter to its center and then gradually decreases in diameter to its discharge outlet.

It has been determined by experiments 105 that to secure the requisite draft or flow of the heat carrying medium, as heated air mingled with the heated gases and other heated products of combustion, through the flue the same must practically be unobstructed 110 throughout its length and present an open passageway to the atmosphere.

The mode of operation is as follows:

The particles of the heat carrying medium, such as heated air, heated gases, and other heated products of combustion, pass 5 upwardly through the flue, inasmuch as they are of less density than the exterior atmosphere and thus create a draft or current.

As is well known, fluids in motion tenaciously cling to the surfaces over which they move in frictional contact following the irregularities and changes in direction of such surfaces, consequently when the said particles of the heat carrying medium, heated air, heated gases and other heated products of combustion, pass into an enlargement S they do not follow straight lines 10 through the interior, but tenaciously cling to the interior surface and in the main follow 15 the interior surface around to the discharge outlet, as shown by the arrows in the two figures. Obviously, in such case heat is transmitted to relatively large areas of surfaces, and the walls defining such surfaces being exteriorly in contact with the water or other fluid in the tank transmit 20 heat to the same. The rising current of the heat carrying medium, inasmuch as it spreads out on entering an enlargement S, 25 is retarded or decreased in velocity and more time is thus provided for transferring to the walls defining the enlargement the heat, or "mode of motion" defined as heat.

Heated water also rises relative to the 30 cold water in a tank, as is well known, consequently as the cross sectional areas of the tank at the dotted lines 1 are less than at the dotted line 2 the upwardly moving current of heated water is retarded and the 35 same held for a longer period of time in contact with the heated surfaces Z of the enlargements S than otherwise would be the case, thus resulting in its receiving more 40 heat or its temperature being raised.

In practice the cross sectional areas of the 45 parts of the flue T, U and V, Figure 1, and parts W and X, Figure 2, as illustrated, are of importance—that is, they should be of the same cross sectional areas, Figure 1, or enlarged upwardly, Figure 2, for if tapered 50 upwardly and inwardly each would act as an injector and discharge the current of the heat carrying medium through the enlargement S and prevent the same passing 55 around the interior surface and in frictional contact therewith.

The apparatus as described can, of course, be applied in connection with any source of heat, as may be determined by special conditions, and at the election or choice of those 60 skilled in the art.

What I claim is:

1. A water heater comprising a tank for water or fluid to be heated, and a hollow flue at the interior of and extending through 65 said tank for the passage of the heat carrying medium; said flue having an enlargement intermediate its ends and the cross sectional area of the flue at its union with the enlargement being not less than the 70 cross sectional area of said flue directly below, whereby said part of the flue below the enlargement will not act as an injector and prevent the heat carrying medium passing 75 around and in contact with the interior surface of the enlargement.

2. A water heater comprising a tank for water or fluid to be heated, and a flue at the interior of said tank having an inlet and outlet and a passage for the heat carrying 80 medium; said flue having a plurality of enlargements, and the cross sectional area of each part of the flue where it connects with an enlargement being of not less cross sectional area than the cross sectional area of 85 the part of the flue directly below the same.

In testimony whereof I affix my signature.
THOMAS D. PILCHER.
